(57) **CLAIM**

I claim the ornamental design for a front shell of thermal cutter, as shown and described.

DESCRIPTION

FIG. 1 is a perspective view of the front shell of thermal cutter showing my new design;

FIG. 2 is a front view thereof;

FIG. 3 is a left view thereof;

FIG. 4 is a right view thereof;

FIG. 5 is a top plan view thereof;

FIG. 6 is a bottom plan view thereof; and,

FIG. 7 is a perspective view of my design for the front shell of thermal cutter in use.

The broken lines are for the purpose of illustrating the environment of the design and form no part of the claimed design. The rear side is substantially flat and unornamented.
